UNITED STATES PATENT OFFICE.

WILHELM VAJNA, OF BUDA-PESTH, AUSTRIA-HUNGARY.

DENTAL NERVE-BROACH.

SPECIFICATION forming part of Letters Patent No. 621,873, dated March 28, 1899.

Application filed August 26, 1898. Serial No. 689,624. (No model.)

To all whom it may concern:

Be it known that I, WILHELM VAJNA, professor, a subject of the Emperor of Austria-Hungary, and a resident of Buda-Pesth, Austria-Hungary, have invented certain new and useful Improvements in Nerve-Broaches, of which the following is a specification.

The present invention relates to improvements in nerve-broaches for dentists' use; and the object of the invention is to provide an instrument of the class described having a loop in the stem thereof, whereby the broach is rendered more flexible, breakage of the portion within the mouth is prevented, and the loop will serve as an indicator or guide as to the position of the point.

The invention is illustrated in the accompanying drawings, in which—

Figure 1 is a side elevation. Fig. 2 is a view at right angles to Fig. 1; and Fig. 3 is a view similar to Fig. 1, the size generally used.

By referring to the drawings it will be observed that the broach is provided intermediate of its point *b* and handle *c* with a coil *a*, or loop *a*, made by turning or coiling the metal one or more times upon itself. By reason of this loop greater flexibility is given to the broach. From the position of the loop the position of the point will be known, and in case of breakage the break is more likely to occur at the loop, whereby this danger of the breaking of the portion within a person's mouth is lessened.

Having thus described my invention, what I claim is—

A nerve-broach having a loop in the body portion thereof, substantially as described.

Signed by me at Buda-Pesth, Austria-Hungary, this 11th day of July, 1898.

WILHELM VAJNA.
